UNITED STATES PATENT OFFICE.

MABELLE A. MEYER, OF NEW YORK, N. Y.

ATOMIZER.

Application filed February 19, 1920. Serial No. 359,840.

To all whom it may concern:

Be it known that I, MABELLE A. MEYER, a citizen of the United States, residing at New York, in the county of New York and State of New York, have invented certain new and useful Improvements in Atomizers, of which the following is a specification, reference being had therein to the accompanying drawing.

10 This invention is a novel atomizer, for example, for use with perfumes or like liquids. The main object of the invention is to afford an ornamental and attractive article of this kind possessing the appearance of a toy figure, namely, a doll figure, and yet which is handy and efficient in use. To the accomplishment of such objects, and other and further objects and advantages which will hereinafter appear, the present invention 15 consists in the novel atomizer and the novel matters of design, construction, arrangement and combination herein illustrated or described.

In the accompanying drawings forming a part hereof, Fig. 1 is a front elevation of the complete article assembled and in readiness for use, certain interior parts being indicated in dotted lines. Fig. 2 is a central vertical section of the same, shown partly in 20 exterior view to indicate the mode of applying pressure to the air bulb.

The bottle A, containing the perfume or other material or liquid to be sprayed, is shown as having a neck B, preferably with 25 exterior screw threads to receive a stopper C in the form of a screw cap. Passing through the screw cap and secured to it is a downwardly extending tube D, reaching nearly to the bottom of the bottle and intended for the exit of perfume when forced 30 by the pneumatic operation. The upper end of the liquid tube D is curved or turned outwardly at E, its extremity or exit F being such as to afford an atomizing or spraying 35 action of the perfume. For causing this operation an air tube G is provided, this leading into the interior of the bottle A. At its exterior portion the tube G is bent sharply downward, and there provided with 40 a pneumatic device or air bulb H, lying close to the bottle A. This bulb constitutes a 45 convenient operating device for effecting

the necessary pressure to force the material to spray as herein described.

The toy figure I, shown as a doll, has below the head portion a body J. These parts I and J may consist of a portion of a hollow celluloid doll, namely, the head, shoulders, arms and a part of the trunk. The lowest portion or extension K of the celluloid figure is shown of such dimensions as to be attached firmly to the screw cap or stopper C, or, if preferred it could be formed or manufactured integrally with the stopper. As shown, the flange or extension 55 K partly overlaps the screw cap, and is there attached, for example, by an adhesive tape or plaster L, wound tightly around in contact with both parts K and C.

At a higher point, and in the center front of the doll's chest is produced an aperture or spray exit M, so located as to correspond with the exit or extremity F of the liquid tube D. The celluloid portions, therefore, not merely conceal and protect the operative 60 parts of the atomizer, but co-operate therewith by affording an aperture at the point where the spray is outwardly directed. Similarly at the rear of the figure is an aperture N, or rather a vertical slot adapted 65 to receive the air pipe G.

A suitable costume for the doll may comprise ribbons or straps O held up by the shoulders, and to which is attached a dress material having a gathering P, surrounding the doll trunk slightly below the aperture M, and flowing skirt portions Q, sufficient to reach to the base or practically cover or conceal the bottle A.

The operating device or bulb it will be 70 noticed is also within and covered by the pliable overhanging portions or skirt of the doll, being located adjacent to the container, yet the bulb is handily operable by simply squeezing from the exterior, as indicated in 75 Fig. 2.

What is claimed is:

A perfume atomizer consisting of the combination of the bottle for containing the material to be sprayed, a doll figure having a body portion and costume portions adapted to enclose the bottle, and a stopper rigid 80 with the body portion of the figure adapted to close the mouth of the bottle, a spray tube 85

extending from the liquid within the bottle through the stopper, thence through the doll figure to an exterior point convenient for atomizer purposes, a spray bulb located between the bottle and the costume portions which enclose it and adapted to be operated while thus enclosed, and a connection from

said bulb to the interior of the bottle for causing the perfume to be delivered through said spray tube to the point of atomization 10 when said bulb is operated.

In testimony whereof, I have affixed my signature hereto.

MABELLE A. MEYER.
